REFRIGERATING APPARATUS

James W. Jacobs, Dayton, Ohio, assignor to General Motors Corporation, Dayton, Ohio, a corporation of Delaware

Application June 18, 1946, Serial No. 677,567

5 Claims. (Cl. 20—35)

1

This invention relates to refrigerator cabinets and particularly to a door structure for such cabinets.

An object of my invention is to provide an improved refrigerator cabinet door construction of low manufacturing cost.

Another object of my invention is to provide a substantially hermetically sealed refrigerator cabinet door with an arrangement for removably securing a seal thereto which is adapted to engage a wall of the cabinet.

A further object of my invention is to lock one sheet-like wall-forming member of a refrigerator cabinet door to the other sheet-like wall-forming member thereof by a portion of one of the members to eliminate the use of screws and bolts or the like.

A still further object of my invention is to provide a refrigerator cabinet door with an inner non-metallic wall member and to secure the same directly to an outer sheet metal wall member thereof by bending a portion of the metal wall over the peripheral edge portion of the inner wall for sealing insulation within the space between the walls.

A more specific object of my invention in securing the inner and outer wall members of a refrigerator cabinet door directly to one another without the use of additional securing means, is to form in the outer wall member a channel and means cooperating with the channel to removably lock a mounting portion of a door seal therein.

Further objects and advantages of the present invention will be apparent from the following description, reference being had to the accompanying drawings, wherein a preferred form of the present invention is clearly shown.

In the drawings:

Fig. 1 is a front view of a refrigerator cabinet having my invention embodied therein and showing a portion of the cabinet door broken away;

Fig. 2 is an enlarged fragmentary sectional view taken on the line 2—2 of Fig. 1, showing the cabinet door in closed position; and

Fig. 3 is a fragmentary sectional view of a portion of the cabinet door showing the position of certain parts thereof prior to locking the door members together.

Referring to the drawings, for illustrating the invention, I have shown in Fig. 1 thereof a refrigerator cabinet of the household type generally designated by the reference character 10. Cabinet 10 includes metal exterior shells or panels 11 and an interior metal liner 12 forming walls of a food storage compartment or chamber 13 with-

2

in the cabinet. Any suitable or desirable insulating material 14 is disposed between the liner 12 and the walls 11 of the cabinet (see Fig. 2). An evaporator or cooling element 15 of a conventional refrigerating system is mounted in the upper part of compartment 13 for cooling and causing circulation of air therein. An insulated frameless door, generally represented by the reference character 16, normally closes an opening in the front wall of cabinet 10, which provides access to the food storage compartment 13 when the door is opened. Another door or cover 17 may close an opening in the front of cabinet 10 leading to a machine compartment located below the food compartment 13 and which houses the refrigerating mechanism operatively connected, in the well-known manner, with the evaporator 15. The food compartment door 16 carries a seal element which engages the front wall of cabinet 10 about the access opening of compartment 13 and my invention is particularly directed to the construction of this door and the method of removably locking the seal element thereon.

In the present disclosure, door 16 comprises a sheet metal wall-forming member 21, shaped to provide the outer face and sides of the door, a non-metallic sheet-like wall-forming member 22, shaped to provide the inner face or wall of the door, and suitable insulating material 23 disposed in the chamber formed between the walls (see Fig. 2). A flange portion on the sheet metal member 21 and spaced from the front face of the door, includes a part 24 which is bent or turned inwardly from the sides thereof. A part of the flange portion on member 21 is thence bent or turned forwardly away from the part 24 and toward the front of door 16 as at 26. Another part 27 of the flange portion on member 21 is bent to parallel the part 24 and the front face of the door. Another part 28 of the flange portion on member 21 is bent rearwardly away from the part 27 toward the rear of the door. Still another part 29 of the flange portion on member 21 is bent to parallel the parts 24 and 27 and to extend back toward the sides of the door. The bent parts 26, 27 and 28 of the flange portion on member 21 form, or provide, a channel 31 (see Fig. 3) extending around the door 16 and in which a seal element adapted to engage the front wall of cabinet 10 is removably mounted, as will be more fully described hereinafter. The wall part 29 of the flange portion on member 21 provides a ledge or support against which the peripheral edge portion 33 of the non-metallic inner door-forming wall 22 abuts. In addition, this

part 28 on member 21 also forms a top wall portion over a part of the width of the channel 31 to provide means for locking the seal element upon the door 16. An extension 32 (see Fig. 3) on the flange portion of the outer metal door member 21 is bent over the peripheral edge portion 33 of the inner non-metallic door wall 22 to firmly secure the wall members directly to one another and to substantially hermetically seal the insulating material 23 therebetween.

The bent parts 26, 27, 28 and 29 in the flange portion of outer metal door wall 21, in addition to providing walls of the channel 31 and strengthening the door after assembly of elements thereof, also prevents twisting of the member 21 during the process of baking a vitreous enamel coating thereon. The inner sheet-like door wall or pan member 22 may be formed of any suitable non-metallic material and painted to match the color of the interior finish of food compartment 13. The member 22 may be formed of a glass-like polystyrene molded from a powder obtainable on the market under the name of "Styron."

As previously mentioned the door 16 carries a rubber element for engaging the front wall of cabinet 10 to seal the compartment access opening from heat leakage about the door. Such a seal element is designated by the reference character 36 (see Fig. 2) and includes a hollow flexible sealing portion 37 engaging the front wall of cabinet 10 and an integral hook-like hollow resilient portion 38 mounted in the channel 31. After the extension 32 is bent from the position thereof, shown in Fig. 3 of the drawings, into the position shown in Fig. 2 of the drawings to lock the door members 21 and 22 together, the resilient mounting portion 38 of seal element 36 is compressed and forced into the channel 31. The portion 38 of element 36 being wedged between the top wall portion 29 and the portions 26 and 27 of door member 21 firmly locks the seal element upon the door 16 without the use of other or additional seal attaching means. The flexible sealing portion 37 of element 36 lies over the extension 32 on wall member 21 to conceal the same from view. While the seal element 36 is firmly attached to door 16 it is, due to the mounting portion 38 thereof being resilient, removable from the door should the same become damaged. By elevating the flexible portion 37 of the seal element 36 and pulling outwardly on the neck or connecting portion intermediate the two portions 37 and 38 thereof, the mounting portion 38 can be removed from the channel 31 to detach the element 36 from the door. It is to be understood that any suitable lubricant or the like may be applied to surfaces of the element 36 during the operation of attaching the same to or detaching the same from door 16 to facilitate slipping of the rubber along the surfaces of door member 21.

It will be seen that I have provided an improved door construction for a refrigerator cabinet door which is simplified and of lower manufacturing cost due to the elimination of screws or other means for locking the inner and outer door-forming walls together. By virtue of my improved door structure the insulation between the sheet-like walls is hermetically sealed and the door hardware, such as the hinges and latch, are attached to the door from the outside thereof so as not to break the hermetic seal of the insulation. Such hinges and latches and the manner of attaching them to a door from the exterior thereof

is well known in the art. For example, tapped and threaded bosses may be welded to the inner surface of the metal door member for receiving attaching screws of the hardware.

5 While the form of embodiment of the invention as herein disclosed, constitutes a preferred form, it is to be understood that other forms might be adopted, as may come within the scope of the claims.

10 What is claimed is as follows:

1. A door for a refrigerator cabinet comprising, an inner sheet-like wall-forming member and an outer sheet-like wall-forming member providing a chamber therebetween, insulating material within said chamber, said outer member having a portion thereof extending inwardly from sides of the door in spaced relation to the front thereof, a part of said portion of said outer member being reversely bent to extend back toward the sides of said door and forming a top wall portion of a channel around said door inwardly of the sides thereof, means for securing said inner member directly to said outer member, said means comprising an extension of said channel top wall portion of said outer member bent over the peripheral edge portion of said inner member, and a seal element including a resilient mounting portion disposed in the channel around said door and an integral flexible portion extending therefrom for sealingly engaging a wall of the cabinet.

2. A door for a refrigerator cabinet comprising an inner non-metallic sheet-like wall-forming member and an outer sheet metal wall member providing a chamber therebetween, insulating material within said chamber, said outer metal wall member having a portion extending inwardly from sides of the door in spaced relation to the front thereof, a part of said portion of said outer metal wall member being reversely bent to extend back toward the sides of said door and forming a top wall portion of a channel around said door inwardly of the sides thereof, means for securing said inner member directly to said outer member, said means comprising an extension of said channel top wall portion of said outer member bent over the peripheral edge portion of said inner member, and a seal element including a resilient mounting portion disposed in the channel around said door and an integral flexible portion lying over and concealing said extension on said outer member and adapted to sealingly engage a wall of the cabinet.

3. A door for a refrigerator cabinet comprising, an inner sheet-like wall-forming member and an outer sheet-like wall-forming member providing a chamber therebetween, insulating material within said chamber, said outer member having a portion extending inwardly from sides of the door thence forwardly toward the front thereof and again inwardly from sides of the door thence rearwardly toward the back of the door to form a channel therearound, a part of said outer member adjacent said rearwardly extending portion thereof being reversely bent to extend back toward the sides of said door and forming a top wall portion of said channel around the door, the peripheral edge portion of said inner member abutting said top wall portion of said channel, means for securing the abutting portions of said members directly to one another, said means comprising an extension of said channel top wall-forming portion of said outer member bent over the peripheral edge portion of said inner member, and a seal element in-

cluding a resilient mounting portion disposed in the channel around said door and an integral flexible portion extending therefrom for sealingly engaging a wall of the cabinet.

4. A door for a refrigerator cabinet comprising, an inner non-metallic sheet-like wall-forming member and an outer sheet metal wall member providing a chamber therebetween, insulating material within said chamber, said outer metal wall member having a portion extending inwardly from sides of the door thence forwardly toward the front thereof and again inwardly from sides of the door thence rearwardly toward the back of the door to form a channel therearound, a part of said outer member adjacent said rearwardly extending portion thereof being reversely bent to extend back toward the sides of said door and forming a top wall portion of said channel around the door, the peripheral edge portion of said inner member abutting said top wall portion of said channel, means for securing the abutting portions of said members directly to one another, said means comprising an extension of said channel top wall-forming portion of said outer member bent over the peripheral edge portion of said inner member, and a seal element including a resilient mounting portion disposed in the channel around said door and secured thereto by said inner member support part of said outer member, and an integral flexible portion for sealingly engaging a wall of the cabinet.

5. A door for a refrigerator cabinet comprising, an inner sheet-like wall-forming member and an outer sheet-like wall-forming member providing a chamber therebetween, insulating material within said chamber, said outer member having a portion thereof extending inwardly from sides of the door in spaced relation to the front thereof, said portion of said outer member being bent to provide a channel around said door 10 and a support for said inner member, means for securing the peripheral edge of said inner member directly to said support on said portion of said outer member, said means comprising an extension of said portion of said outer wall bent over the edge portion of said inner member, and a seal element including a resilient mounting portion disposed in the channel around said door and secured thereto by said inner member support part of said outer member, and an integral flexible portion for sealingly engaging a wall of the cabinet.
